[57] CLAIM

The ornamental design for a hair dryer stand, as shown and described.

DESCRIPTION

FIG. 1 is a top perspective view of a hair dryer stand showing my new design;

FIG. 2 is a front elevational view thereof;

FIG. 3 is a right side elevational view thereof, the side opposite being a mirror image of the side shown;

FIG. 4 is a rear elevational view thereof;

FIG. 5 is a top plan view thereof; and,

FIG. 6 is a bottom plan view thereof.

The broken line showing of hair dryer in FIG. 1 is for illustrative purposes only and forms no part of the claimed design.

FIG. 5

FIG. 6

FIG. 1

FIG. 2
